CRIB

Marie A. Kirkpatrick, Grand Rapids, Mich., assignor to Lullabye Furniture Corporation, Stevens Point, Wis., a corporation of Wisconsin

Application October 24, 1957, Serial No. 48,224

Term of patent 14 years

(Cl. D5—5)

Fig. 1 is a perspective view of a crib showing my new design; and

Fig. 2 is a detail sectional view taken on the line 2—2 in Fig. 1.

The dominant features of my design reside in those portions shown in full lines in the drawing. The back of the panel is plain and unornamented.

I claim:

The ornamental design for a crib, as shown and described.
